CLAIM

The ornamental design for a food recycler cover, as shown and described.

DESCRIPTION

FIG. 1 is a top perspective view of a food recycler cover showing the first embodiment of our new design;
FIG. 2 is a top view of the food recycler cover of FIG. 1;
FIG. 3 is a front view of the food recycler cover of FIG. 1;
FIG. 4 is a right side view of the food recycler cover of FIG. 1;

FIG. 5 is a top perspective view of a food recycler cover showing the second embodiment of our new design; and,
FIG. 6 is a top view of the food recycler cover of FIG. 5. Portions of the food recycler cover and the food recycler environment shown in broken lines form no part of the claimed design.
